UNITED STATES PATENT OFFICE.

WILLIAM GORDON, OF BOSTON, MASSACHUSETTS.

SOLE-PROTECTOR.

SPECIFICATION forming part of Letters Patent No. 276,803, dated May 1, 1883.

Application filed October 9, 1882. (No model.)

To all whom it may concern:

Be it known that I, WILLIAM GORDON, of Boston, in the county of Suffolk and State of Massachusetts, have invented certain Improvements in Sole-Protectors, of which the following is a specification.

This invention is an improvement on the device for protecting sole-edges for which Letters Patent of the United States were issued to me May 23, 1882, No. 258,228, and has for its object to provide a device adapted to protect the bottom as well as the edges of the sole after the latter has been finished and while the boot or shoe is undergoing the treeing operation.

To this end the invention consists in the improved device which I will now proceed to describe and claim.

Of the accompanying drawings, forming a part of this specification, Figures 1 and 2 represent perspective views of a sole-protector embodying my invention, showing both sides of the same. Fig. 3 represents a transverse section of the same applied to a sole.

In carrying out my invention I form a sole-protector, A, adapted to cover the bottom and edge of a boot or shoe sole. Said protector is made in two parts, 2 3, each of which comprises about one-half of the bottom and edge protecting portions of the device, and a connecting-strip of elastic material, which consti-

tutes also a portion of the bottom and edge protecting portions, and allows the parts 2 3 to be separated and holds their edges with a yielding pressure against the edges of a sole, S, to which the device is applied. The parts 35 A A may be made of leather, leather board, or any other suitable material, and may be molded or otherwise formed. The elastic part 4 is preferably made of a suitable elastic fabric.

It will be seen that the device is capable of 40 being quickly applied to soles of different sizes and of holding itself in place when applied, so that an efficient protector is provided, which will protect the buffed bottoms of soles, as well as the edges, from being soiled and defaced 45 while the final treeing operation is being performed.

I claim—

The improved sole-protector composed of the two parts adapted to cover the bottom and 50 edges of the sole, and the intermediate elastic part or connection, as set forth.

In testimony whereof I have signed my name to this specification, in the presence of two subscribing witnesses, this 26th day of September, 55 1882.

WILLIAM GORDON.
